UNITED STATES PATENT OFFICE.

FRANK F. NEAL, OF CHICAGO, ILLINOIS, ASSIGNOR OF ONE-HALF TO FRANK W. NEAL,
OF CHICAGO, ILLINOIS.

MONEY-CHANGER HOLDER.

Application filed July 26, 1926. Serial No. 125,012.

My invention relates to improvements in money changer holders, and it consists in the combinations, constructions, and arrangements herein described and claimed.

5 An object of my invention is to provide a money changer holder which is adjustable, and which may firmly hold the changer in a fixed position, thus obviating the necessity of the user constantly holding the changer 10 in place with one hand as he walks or stoops or bends his body in any manner.

A further object of my invention is to provide a device of the type described which protects the clothing of the user.

15 A further object of my invention is to provide a device of the type described in which the money changer is held in the center as well as at each end.

20 A further object of my invention is to provide a device of the type described in which the money changer may readily be removed from the holder, and the holder readily removed from the user.

25 Other objects and advantages will appear in the following specification, and the novel features of the invention will be particularly pointed out in the appended claim.

30 My invention is illustrated in the accompanying drawings, forming part of this application, in which—

Figure 1 is a plan view of the device, a portion thereof being broken away, and

Figure 2 is a section along the line 2—2 of Figure 1.

35 In carrying out my invention, I make use of a money changer 1 having rods 2 and 3 disposed at each end thereof, as clearly shown in Figure 1. An outwardly extending flange 4 extends between the rods 2 and 3.

40 I provide a guard 5 which is rectangular in shape and preferably formed of leather. The guard 5 is provided with elongated slots 6 and 7 which are positioned at each end 45 and substantially adjacent the upper edge thereof. A strap 8 is secured at its mid point to the guard 5 by means of a fastener 9. An end 10 of the strap is passed around the rod 2 and is secured to the body portion 50 of the strap by means of a fastener 11. The other end 12 of the strap 8 is passed around the rod 3 and is secured to the body portion 55 of the strap by means of a fastener 13.

A belt is provided having substantially identical parts 14 and 15. These parts are 55 secured together by means of a buckle 16. As the parts are substantially identical in construction, a description of one will apply to both. The free end 17 of the part 15 is passed around the rod 3 through the slot 6 in the guard 5, through an adjustable catch 18, and secured to the body portion of the part 15 by means of a fastener 19.

From the foregoing description of the various parts of the device, the operation 65 thereof may be readily understood. The buckle 16 may be separated, the parts 14 and 15 passed around the waist of the user, and the buckle again placed together. The parts 14 and 15 may be adjusted by moving 70 the adjustable catches 18 to any desired position. The guard 5 is positioned between the metal parts of the money changer and the clothes of the user, and in this manner, the clothes are protected. The substantially 75 wide belt firmly holds the money changer and the guard in a predetermined position, irrespective of the position of the user.

The money changer may be removed from the user in various ways, such as separating 80 the buckle 16, or releasing the ends 17 of the parts 14 and 15 from the catches 18 and from the rods 2 and 3. The guard 5 may now be removed from the strap 8 by separating the fastener 9. It is obvious that the 85 guard and the strap 8 may be removed together by releasing the ends 10 and 12.

The guard 5 serves also the purpose of a pad for preventing the money changer from coming forcibly in contact with the 90 body of the user.

I claim:

The combination with a money changer having rods disposed at each end thereof, of a money changer holder comprising a strap having its ends removably secured to said rods, a guard removably secured to said strap and having relatively large elongated slots in each end thereof, a belt having two substantially identical parts secured together by a buckle, and adjustable catches disposed upon each of said parts, the free ends of said parts being passed around said rods through said openings and removably secured to said catches.

FRANK F. NEAL.
